UNITED STATES PATENT OFFICE.

EMMA W. COLMAN, OF TENAFLY, NEW JERSEY.

DIAPER-SKIRT.

1,260,873.

Specification of Letters Patent. Patented Mar. 26, 1918.

Application filed October 24, 1916. Serial No. 127,423.

To all whom it may concern:

Be it known that I, EMMA W. COLMAN, a citizen of the United States, and a resident of Tenafly, in the county of Bergen and 5 State of New Jersey, have invented a new and Improved Diaper-Skirt, of which the following is a full, clear, and exact description.

My invention has for its object to provide 10 an envelop diaper skirt which will serve as a substitute for a flannel petticoat, and which will remain in normal position and protect the child's abdomen and loins, no matter in what position the child may be 15 held. The envelop diaper skirt, when used, covers the diaper and gives warmth and comfort where most needed.

Another object of the invention is to provide 20 an envelop diaper skirt having a waist portion, the bottom of which is curved outwardly and upwardly from the back, the top of the skirt portion being curved outwardly and downwardly from the back, which increases the depth of the back of the skirt 25 relatively to the front, the width of the back of the skirt portion being increased by gathering the top of the back of the skirt portion where it is secured to the waist portion. This construction not only increases 30 the size of the skirt where desired, but it shapes the skirt portion so that it will fit the child's legs.

Additional objects of the invention will appear in the following specification, in 35 which the preferred form of the invention is disclosed.

In the drawings similar reference characters denote similar parts in all the views, in which—

40 Figure 1 is a perspective view showing how the envelop diaper skirt is worn by a child;

Fig. 2 is a view illustrating the envelop diaper skirt in open position;

45 Fig. 3 is a view illustrating the manner in which the parts of the envelop diaper skirt are fastened together; and

Fig. 4 is a plan view showing the form in 50 which the waist portion and the diaper skirt are cut before being sewed together.

By referring to the drawings, it will be seen that the skirt portion 5 is cut on the bias along its upper edge 6, the sides 7 of the diaper skirt converging downwardly to a 55 point 8, the upper portions of the sides 7 being cut off at 7^a, as illustrated in the draw-

ings. From the back 9, the upper edge 6 of the skirt portion is curved or inclined outwardly and downwardly, the bottom edge 11 of the waist portion 10 being curved or inclined from its back outwardly and upwardly. The back 9 of the skirt portion 5 is gathered, as best illustrated in Fig. 2 of the drawings, and the upper edge 6 of the skirt portion 5 is sewed to the bottom edge 65 11 of the waist portion 10. This construction not only lengthens the back of the envelop diaper skirt portion 5 relatively to its front, but greater fullness is obtained at the back of the diaper skirt because of the gathering of the top of the diaper skirt portion at its back, where it is secured to the waist portion, and because of the fact that the upper edge 6 of the diaper skirt is cut on the bias. 70

The upper edge of the waist portion 10 is cut with a collar portion 12, and with two arm openings 13, one disposed at each side of the collar portion 12. The sides of one of the arm openings 13 converge upwardly in a 80 general direction relatively to the sides of the other arm opening 13, so that the collar portion 12 will fit snugly around the back of the child's neck, and the collar portion 12^a will fit snugly around the front of the child's 85 neck.

It will be understood that the waist portion 10 may be manufactured from cotton or other warmer goods, if desired, and that the diaper skirt 5 will preferably be manufactured of flannel or other absorbent material. The terminals 13^b at the upper edge 90 of the waist portion may project upwardly farther than the terminals 13^a, so that the terminals 13^a and 13^b may be secured together over the front of the child. I prefer 95

to make button-holes 14 in the terminals 13^b, and to secure buttons to the terminals 13^a; but it will be understood that any other fastening means may be employed. Buttons 100 15 are preferably secured to one side of the waist portion 10, and of the diaper skirt portion 5, and button-holes 16 are made in the other side of the waist and of the skirt portion, so that the sides of the waist and skirt portions may be fastened together at 105 the front of the child, there being a button-hole 17 at the end 8 of the diaper skirt portion 5 which may be disposed over the lower button 15, as illustrated in Fig. 3 of the 110 drawings. In addition, buttons 18 are secured to the diaper skirt at 20, these buttons

18 being provided for disposal within button-holes 19 so that the sides 7 of the diaper skirt portion 5 may be held snugly around the child's legs. The cutting of the top 6 5 of the diaper skirt portion 5 outwardly and downwardly from the back of the diaper skirt portion not only serves to lengthen the rear of the diaper skirt portion relatively to its front, but it also serves to shorten the 10 sides 7 of the diaper skirt portion which assists in fitting the diaper skirt when the end 8 of the diaper skirt is drawn up, and the lower button 15 is disposed in the button-hole 17.

15 It will be understood that not only may any suitable fasteners be used to secure the terminals 13^a and 13^b together, but that any suitable fasteners may be employed to secure the front of the waist and skirt portions together, and also for holding the lower end 20 8 of the skirt upwardly and the sides 7 of the skirt snugly around the child's legs.

The diaper skirt may be removed and another diaper skirt may be substituted therefor without raising the child, since all the buttons or other fasteners may be freed while the child is on its back, and the diaper skirt may be drawn away and another diaper skirt may be pulled into position while the 30 child remains on its back.

Having thus described my invention, I claim as new and desire to secure by Letters Patent;

1. In an envelop diaper skirt, a waist 35 member which opens in front and which has a bottom edge, and a skirt member which opens in front and which has an upper edge and sides which converge downwardly, the said edge of one of the members being inclined from its back outwardly in the general direction of its body, the upper edge 40 of the back of the skirt member being gathered and being secured to the bottom of the waist member so that when the sides of the 45 waist member are secured together at the front of an infant the upper portions of the converging sides of the skirt member will

be drawn upwardly because of the inclined edge, to narrow the skirt member at the infant's legs, the bottom of the skirt member 50 being normally disposed upwardly between the infant's legs and secured.

2. In an envelop diaper skirt, a waist member which opens in front and which has a bottom edge, and a skirt member which 55 opens in front and which has an upper edge and sides which converge downwardly, the said edge of one of the members being inclined from its back outwardly in the general direction of its body, and being secured 60 to the edge of the other member so that when the sides of the waist member are secured together at the front of an infant and the bottom of the skirt member is drawn up in normal position, leg openings will be 65 formed by the skirt member at its said converging sides which are positioned wholly at the front of the diaper skirt, and with the diaper skirt at the sides of each leg opening extending upwardly and inwardly. 70

3. In an envelop diaper skirt, a waist member which opens in front and which has a bottom edge, and a skirt member which 75 opens in front and which has an upper edge cut on the bias and sides which converge downwardly, the said edge of one of the members being inclined from its back outwardly in the general direction of its body, and being secured to the edge of the other member so that when the sides of the waist member are secured together at the front of an infant and the bottom of the skirt member is drawn up in normal position, leg 80 openings will be formed by the skirt member at its said converging sides which are positioned wholly at the front of the diaper skirt, and with the diaper skirt at the sides of each leg opening extending upwardly and inwardly. 85
